UNITED STATES PATENT OFFICE

2,046,582

MECHANICAL PENCIL

Harry S. Richer, Chicago, Ill., assignor, by mesne assignments, to Melrose Products Co., Inc., a corporation of Illinois

Application May 26, 1934, Serial No. 727,664

11 Claims. (Cl. 120—18)

The primary object of the invention is to provide a mechanical pencil having a minimum number of parts, each of which is designed so that it may be made by relatively simple manufacturing operations and so that the mode of interfitting of the various parts permits of relatively large tolerances in the manufacture of each part and provides an accurate and satisfactory assembled structure.

10 Another object is to provide a pencil in which movement of the parts is resisted frictionally to just such an extent that no unwanted movement occurs but yet the parts may be freely operated when desired.

15 A more detailed object is to provide in a pencil of this type a novel means for securing and supporting the tip of the pencil in the barrel, which permits the tip to operate satisfactorily and which has a relatively simple structure.

20 It is also an object to provide a novel structure for projecting or advancing the lead, such structure lending itself to inexpensive production and permitting the lead to be readily replaced.

Another object resides in the provision of a 25 novel means for supporting an eraser.

Other objects and advantages will become apparent from the following description taken in connection with the accompanying drawings, in which:

30 Figure 1 is a longitudinal section of a pencil embodying the features of the invention.

Fig. 2 is a longitudinal section of the tip structure of the pencil shown in Fig. 1.

Fig. 3 is an end view of the forward end of the 35 pencil.

Fig. 4 is a transverse section taken on the line 4—4 of Fig. 2.

Fig. 5 is a transverse section taken on the line 5—5 of Fig. 1.

40 Fig. 6 is a transverse section taken on the line 6—6 of Fig. 1.

Fig. 7 is a longitudinal fragmentary section of a pencil having a modified form of tip structure.

Fig. 8 is a transverse section taken on the line 45 8—8 of Fig. 7.

Fig. 9 is a longitudinal fragmentary section of a pencil having another modified form of tip structure.

Fig. 10 is a transverse section taken on the 50 line 10—10 of Fig. 9.

Fig. 11 is a transverse section similar to Fig. 5 but showing a modified form of barrel.

The preferred embodiment of the invention 55 comprises generally a barrel within which is located a means for advancing the lead of the

pencil and operated by a rotative movement. Co-operating with said means is a guide member which is supported by the barrel. To operate the lead advancing means is a structure at one end of the barrel which in the preferred form constitutes a tip at the forward end of the barrel for slidably supporting the lead. At the other end of the barrel is a sleeve for supporting an eraser, the sleeve being yieldably held in place by the guide member.

5 In the following detailed description, it will be noted that the various parts comprising the above-mentioned elements of the invention are of such a nature that they may be made by a few simple manufacturing operations and that very few parts are required. It will also become apparent that the various parts do not require close tolerances in their manufacture in order to coact properly with the other parts. The pencil may therefore be made at a low manufacturing cost.

10 As shown in the drawings, the barrel indicated at 20 is an elongated tube preferably hexagonal in shape and made of metal or composition. Within the barrel is a guide member 21 for supporting a lead advancing means. The guide member is preferably made from a thin-walled channel-like part having portions of its walls formed radially inward to provide a plurality of longitudinal ribs 22 (see Figs. 5 and 6) while part of the outer portion of the wall is shaped to fit 30 snugly within the barrel to prevent relative rotation therebetween. The ribs 22 together provide a central guideway 23, while the space between the ribs and within the guide member forms a slot opening from the central guideway 35 23 and providing an eccentric guideway 24, both guideways extending longitudinally of the pencil to cooperate with the lead advancing means. A plurality of such eccentric guideways or channels may thus be provided, as indicated in Figs. 5 40 and 6, and between these channels are other compartments, each open at the top and of a size capable of receiving a lead to be held in reserve for use whenever needed. By the provision of the ribs 22, the guide member is somewhat yieldable in character both internally and externally so that the barrel may be forced on the guide member if the latter is slightly large. Thus, the 45 internal dimensions of the barrel and the external dimensions of the guide member do not have to be held to close limits in order to have a tight fit with one another.

The means for advancing the lead, in the present instance, is of an especially inexpensive construction. It comprises a helical member 25 ro- 55

tatably supported by the central guideway 23. The member 25 is formed from a flat strip of metal coiled into a helix with the turns thereof spaced from each other to provide a helical slot. 5 In manufacturing this member, a helix of indefinite length may be wound on an automatic coiling machine and then cut into the proper lengths. The lead, indicated at 26, may extend into the forward end of the helical member in 10 one position of adjustment, while in the rear end is a plunger 27 made of a piece of wire rod or cast metal. The plunger is adapted to be moved longitudinally, to push the lead forward, by the helical member. To this end, the rear end of 15 the plunger is formed laterally as at 28 to extend through the slot between the turns of the helix and into the eccentric guideway 24 where it is held against rotation. Thus, on rotation of the member 25, the plunger is moved longitudinally 20 by the helix. The helical member and plunger accordingly serve as two co-acting screw elements which, together with the cooperating eccentric channel, constitute the lead propelling mechanism for the pencil. Before assembling the helical member in the guide member, the former may be bowed slightly. The insertion of the helical member in the guide member straightens the former, but sufficient friction is produced therebetween so that the helical member will rotate only on manual operation. 30

The tip structure, which in the present instance is the means for operating the lead advancing means, is rotatably mounted in a tapered portion 30 of the forward end of the barrel 20. 35 The tip comprises a hollow member 31 tapered forwardly and longitudinally split at 32 from its forward end inwardly to provide spring fingers for slidably supporting the lead 26. The rear portion of the tip is reduced in diameter as at 33 40 to enter the barrel and to provide a shoulder 34 abutting the end of the barrel.

While the tip is rotatable in the barrel, it is desirable that such rotation occur only when the tip is manually operated, so that the lead will not be advanced except when desired. To this end, 45 a small amount of friction between the tip and the barrel is purposely provided, the friction normally holding the tip against accidental rotation. Preferably the tapered end 30 of the barrel is provided with means for producing such friction, and in the present instance said means comprises a ring or bushing 35 rotatably supporting the reduced portion 33 of the tip and non-removably fixed in the tapered end of the barrel. The 50 ring 35 may be a plain unbroken band having a fairly snug fit on the reduced portion, but preferably it is a longitudinally split resilient ring having its ends slightly offset, as shown at 36 in Fig. 4, so that one end will have a frictional drag 55 on the tip.

The tip is rigidly secured to the helical member 25 by inserting the forward end of the helical member into the rear end of the reduced portion and then pressing the reduced portion to slightly deform it and force a part of the metal thereof 60 into the helical slot as shown at 37. In the preferred form of tip structure, such pressing action may be exerted at the same time that a sleeve 38 is placed on the reduced portion 33 to hold the ring 35 in place on the tip. Thus, by the one 65 pressing operation, the sleeve 38 is rigidly secured to the tip and the tip is rigidly secured to the helical member.

An important feature of the tip structure is 70 that it is rotatably supported at two spaced

points. For this purpose, the forward end of the guide member 21 is countersunk at 40 to receive the inner end of the reduced portion 33 and the sleeve 38. Thus, the tip is rotatably supported by the ring 35 and by the guide member 21 at 5 points spaced a substantial distance apart so that the tip will be held in its proper position in spite of lateral pressure exerted thereon when the pencil is in use. The tip may be provided with knurled portions 39 to facilitate manual operation thereof. 10

To attach an eraser to the pencil, the guide member 21 at its rear end extends beyond the barrel a substantial distance to receive a sleeve 41 which is yieldable to some extent when in place. 15 Because of the yielding nature of both the guide member and the sleeve 41, the latter is removably held in place. The eraser, indicated at 42, may be clamped in the sleeve 41 by forming an inwardly turned rib 43 and an inwardly turned 20 flange 44 on the outer end of the sleeve.

In the modified form of tip structure shown in Figs. 7 and 8, the tapered end 30 of the barrel is constructed to provide the frictional support for the tip. As illustrated, the end of the barrel 25 is provided with an inwardly extending rounded rib 45 shaped to fit in a corresponding annular groove cut in the reduced portion 33 of the tip. To permit the tip to be readily inserted in the barrel, the tapered portion 30 is longitudinally 30 split from the forward end inwardly as at 46, so that the end of the barrel may spring open sufficiently to permit the rib 45 to slide over the reduced portion 33 of the tip and then snap into its groove. 35

In the modified form shown in Figs. 9 and 10, a square-shouldered rib 47 of greater length is provided on the end of the barrel, and the latter is longitudinally split as at 48 so that the rib 47 40 may be slipped over the reduced portion 33 of the tip and then snapped into a groove in the tip.

While the preferred cross-sectional form of the barrel is hexagonal, it may also be made round as shown in Fig. 11 or other shapes not shown herein. When so shaped, the guide member is correspondingly modified so that part of the outer portions of its walls are arcuate as shown at 50 to fit snugly within the barrel. By forcing the forward end of the guide member into the tapered portion of the barrel, sufficient friction may 55 be provided to prevent relative rotation. But, if it be deemed advisable, the barrel may be provided with some means to prevent relative rotation of the guide member such as indenting the 60 barrel at one point.

In the operation of the pencil, assume that the parts are assembled as shown in Fig. 1. To advance the lead as it wears down, the tip is rotated relative to the barrel and the helical member 21 rotates in the central guideway 23. Since the plunger 27 has a portion extending through the helical slot of the member 21 and is held against rotation by the eccentric guideway 24, the plunger forces the lead forward. 65

When one piece of lead is used up, the eraser 42 and its sleeve 41 are removed and the tip is reversely rotated until the laterally formed portion 28 of the plunger passes out of the helical slot at the rear end. The plunger may thus be 70 manually withdrawn and a new piece of lead inserted into the helical member. The plunger is then reinserted and moved forwardly by rotation of the tip until the lead protrudes a suitable distance from the forward end of the tip. 75

The helical member permits the plunger to operate through a relatively long range of movement so that pieces of lead of considerable length may be employed.

5 It will be noted that the parts of the pencil may be readily formed by simple manufacturing operations and are therefore relatively inexpensive. The barrel 20 and guide member 21 may be formed from tubing, while the helical member 25 and plunger 27 may both be manufactured easily. The barrel will fit snugly on the guide member because of the yieldable nature of the latter, and the helical member and plunger do not have to be held to close limits in their dimensions in order to assemble properly and operate satisfactorily. The tip structure is also of simple construction and because of the yielding, resilient nature of some of the parts thereof, the parts hold together and operate properly in spite of any slight variations of size. Thus, the tolerances allowed in the manufacture of the various parts greatly reduce the cost of producing them.

It will also be noted that because of the resilient nature of many of the parts, a friction is created between relatively movable parts, which prevents accidental movement thereof but permits free manual operation.

I claim as my invention:

1. A pencil of the character described comprising, in combination, a barrel, a guide member enclosed by the barrel, said barrel having a portion extending beyond the guide member at one end, means for advancing the lead comprising a rotatable helical member supported by said guide member, and a plunger within the helical member having one end formed to extend between the turns of the helical member for engagement with the guide member, and means for rotating the helical member comprising a tip for holding the lead, said tip having a shank extending into the barrel with the shank rotatably supported at spaced points by the extending portion of the barrel and by the adjacent end of the guide member.

45 2. A pencil of the character described comprising, in combination, a barrel, rotatable means within the barrel for advancing the lead, a rotatable tip mounted in one end of the barrel for slidably supporting the lead and for actuating said rotatable means, and a longitudinally split resilient ring interposed between the end of the barrel and the tip and having its ends laterally offset to bear against the tip and frictionally resist unrestricted rotation thereof.

55 3. A pencil of the character described comprising, in combination, means within the barrel for advancing the lead including a rotatable member, a rotatable but non-removable hollow tip mounted in one end of the barrel for slidably supporting the lead and for actuating said means, said tip having a portion of reduced diameter positioned within the barrel and providing a shoulder abutting the end of the barrel, the end of said rotatable member being positioned within

65 the reduced portion of the tip, a ring interposed between said reduced portion and the barrel, and a locking sleeve positioned on the reduced portion for holding said ring in position, said sleeve being pressed on said reduced portion to form a rigid connection therewith and to force the reduced portion against said rotatable member to provide a rigid connection therebetween.

4. A pencil of the character described comprising, in combination, a tubular barrel, an elongated guide member, the guide member having

a portion formed to provide a pair of longitudinally extending guideways opening laterally into each other, said portion extending within the barrel and out beyond the upper end thereof, one guideway being centrally positioned and the other eccentrically positioned with respect to the barrel axis, a tip rotatably supported at one end of the barrel, an operating member open at its upper end and secured to the tip for rotation therewith and positioned within the central guideway, the 10 operating member having a helical slot constituting a guideway, a plunger positioned within the operating member and movable thereinto and therefrom through the open upper end thereof, the plunger having a laterally formed portion 15 extending through the helical guideway into the eccentric longitudinal guideway whereby the plunger will be shifted endwise upon rotation of the tip, and a closure for the upper end of the pencil applied over the guide member portion 20 which extends beyond the upper end of the barrel.

5. A pencil of the character described comprising, in combination, a tubular barrel, an elongated guide member, the guide member comprising 25 a channel having longitudinally extending portions formed radially inwardly to provide a central guideway and extending within the barrel and out beyond the upper end thereof, a tip rotatably mounted at one end of the barrel, an 30 operating member open at its upper end and secured to the tip for rotation therewith and positioned within the central guideway, the operating member having a helical slot constituting a guideway, a plunger positioned within the operating member and movable thereinto and therefrom through the open upper end thereof, the plunger having a laterally formed portion extending through the helical guideway into the channel whereby the plunger will be shifted endwise 40 upon rotation of the tip, and a closure for the upper end of the pencil applied over the guide member end which extends beyond the upper end of the barrel.

6. In a pencil, the combination of a barrel open 45 at its upper end, lead propelling mechanism within the barrel comprising an elongated guide member affixed to the barrel and extending in part out beyond the upper end thereof, the guide member with its extending part being of tubular 50 form with its walls so shaped as to provide a central guideway in lateral communication with eccentric channels, and a closure for the upper end of the pencil applied over and frictionally held in place by the extending part of the guide 55 member.

7. In a pencil, the combination of a barrel open at its upper end, lead propelling mechanism within the barrel comprising a guide member of uniform cross-section throughout its length affixed 60 to the barrel and extending in part out beyond the upper end thereof, and a closure for the upper end of the pencil applied over the extending part of the guide member.

8. In a pencil, the combination of a barrel open 65 at its upper end, lead propelling mechanism within the barrel comprising coacting screw elements positioned centrally within the barrel and an elongated guide member affixed to the barrel, the guide member having its walls so formed as to 70 provide for one of the screw elements a central guideway in lateral communication with an eccentric channel adapted to receive a portion of a second screw element and to one side of the channel a longitudinally disposed compartment 75

open at the upper end of the barrel, said guideway, channel and compartment extending in part beyond the upper end of the barrel and a closure for the guideway, channel and compartment applied over the extending part thereof.

9. In a pencil, the combination of a barrel open at its upper end, lead propelling mechanism within the barrel including a longitudinal guide member affixed within the barrel and extending in part beyond the upper end thereof, said guide member being tubular with its walls bent radially inward to provide guideways, and a closure for the upper end of the pencil applied over the extending part of said guide member, the bending of the walls in the aforesaid manner providing a yielding structure frictionally retaining the closure in place.

10. In a pencil, the combination of a barrel open at its upper end, lead propelling mechanism

within the barrel including a longitudinal guide member affixed within the barrel and extending in part beyond the upper end thereof, said guide member comprising a tubular element having longitudinal ribs extending radially inward to provide guideways, and a closure for the upper end of the pencil fitting over the extending part of the guide member and frictionally held in place by the yieldability of the guide member provided by the longitudinal ribs therein.

11. In a mechanical pencil, the combination of lead propelling mechanism including a guide member having a shape providing a plurality of longitudinal guideways utilized in propelling the lead, and a closure fitting over one end of said guide member, said shape of the guide member being radially yieldable and thereby frictionally holding said closure in place.

HARRY S. RICHER.
